DISPENSING APPARATUS

Lue O. Garner and Fred Montesi,
Memphis, Tenn.

Application May 18, 1938, Serial No. 208,522

6 Claims. (Cl. 312—36)

This invention relates to machines for cooling and dispensing small packages such as cans or bottles, as of soft drinks, beer and the like, which is desired to keep ice cold and which are to be dispensed one at a time.

The invention relates to means by which the bottles are stored in the machine; to means by which they may feed by gravity from the storage space into the cooling apparatus; to means by which various portions of the storage space are made accessible for loading; to means by which storage may be accomplished in a plurality of superposed tiers and in which each successive tier is effective to retain the underlying tier until such superposed tier is entirely empty.

The invention relates further to the means by which the cooling mechanism is advanced by step by step motion; to means by which such advancing motion accomplishes the ejection of the bottles or cans; to means by which the ejection of the cans temporarily opens the apparatus for the proper discharge of the cans or bottles, and to means by which the cans or bottles, as they are discharged, are so turned that eventual delivery will be in a longitudinal direction and by sliding instead of rolling movement.

The objects of the invention are:

To provide an insulated casing adapted to contain a chilled liquid in which the articles are submerged for cooling.

To provide in connection with such a casing a storage compartment adapted to receive and hold the articles in a plurality of superposed tiers.

To provide in such a storage compartment means for separating and individually supporting the tiers, which means are displaceable to provide access to underlying chamber portions for filling; and

To provide means in connection with such spacing means for retaining the tier of articles therebelow until complete discharge from such retaining means is accomplished.

To provide means for advancing the cooling mechanism step by step to bring the cans or bottles into position for delivery.

To provide means in connection with such advancing means for ejecting the cans or bottles as they reach the point of delivery, and for accelerating their ejection.

To provide means actuated by ejection of a can or bottle for opening the casing during the action of ejection; and

To provide means for alining the ejected bottles or cans for longitudinal discharge.

The means by which the foregoing and other

objects are accomplished, and the method of their accomplishment will readily be understood from the following specification on reference to the accompanying drawings, in which:

Fig. 1 is a sectional side elevation of the device with one side of the casing removed.

Fig. 2 is a plan of a portion of the device with the top open, the plan showing one complete unit.

Fig. 3 is a sectional elevation taken on the line III—III of Fig. 1 showing one unit and part of a second unit.

Fig. 4 is a fragmentary end elevation of the casing showing the top swung open for access to the interior as for refilling.

Fig. 5 is a partial end elevation of the opposite end of the casing showing the delivery chutes and pockets and the handle portion of the actuating mechanism.

Fig. 6 is a fragmentary sectional elevation showing the advancing mechanism and the ejection mechanism, the view being taken as on the line VI—VI of Fig. 7.

Fig. 7 is a corresponding sectional view taken on the line VII—VII of Fig. 1; and

Fig. 8 is a fragmentary section taken on the line VIII—VIII of Fig. 6.

Referring now to the drawings in which the various parts are indicated by numerals:

10 is a casing having side and bottom walls and a top 11, preferably hinged along one side edge 30 as by hinges 12 to provide access to the interior for loading and other purposes. The side, bottom, and top walls have a lining 13 which forms a tank for the reception of a liquid such as salt water which may be chilled and in which liquid 35 the bottles or cans are immersed for cooling before they are dispensed. This cooling is effected by a coil 14 through which a refrigerant is circulated, as by an usual type of refrigerating apparatus 15.

Preferably the front portion of the casing, serving as a submerged tank, is of considerably greater depth than the rear portion, the bottom wall of this rear portion 16 being downwardly and forwardly inclined so that cans or other articles 45 placed thereon will roll toward the front and deeper portion of the casing. The casing may be of a width to accommodate one or more chilling and delivering units, the present drawings show one such unit complete and a portion of a second 50 unit, but not being intended to limit the number of units for which it may be constructed.

The rear and shallower portion of the casing constitutes a storage chamber from which the articles are continuously fed to the chilling and 55

dispensing apparatus. This storage chamber may be entirely above the liquid level or may be partially submerged, the partially submerged type being here shown. The storage chamber is provided with a holder for each unit of the apparatus. These holders each comprise side walls 20, and end wall 21 and a bottom 22, the deeper end of the channels being open and the bottom 22 having the same slope as the bottom of the storage chamber. Hingedly connected to the end wall 21 are shelves 23, 24, 25, the shelves being spaced apart a somewhat greater distance than the diameter of cans or bottles which are to be stored in the channelway. At the forward or open end of the channelway the shelf 23 is provided with a support which may be a transverse rod 26, and the shelves 24 and 25 are provided with supports 27 and 28 respectively, which supports are lugs projecting from the opposite side walls 20 of the channelway. The lower shelf 23 is provided with oppositely disposed cut-away portions 29 so that it may be swung downward past both the lugs 27 and 28 and against the supporting rod 26. The shelf 24 is provided with a more restricted cut-away portion 30 which will pass the lugs 28 only, so that it may be swung downward against the lugs 27 and be supported thereby. The upper shelf 25 has no cut-away portions and is supported by the lugs 28. Each of the shelves has secured to its outer end a thin flexible extension 31, 32, and 33, respectively, each of these extensions having a downwardly turned lip 34 adapted, when the extension is depressed by the weight of a supporting can or package, as the package 35, to retainingly engage an underlying can or bottle, these packages, as the package 35, being indicated by light dot-dash lines.

Opposite the channelways are submerging devices each comprising a shaft 40, journaled at its opposite ends in bearings 41, supported by suitable frame members 42. Mounted on the shaft 40 is a hub 43 and a disc 44 which is secured to the hub as by rivets 45. Spaced from the disc 44 are two discs 46 and 47, the first disc being fairly close to the disc 44 and the other disc spaced from the first disc somewhat less than the length of the package to be handled. The two discs 46 and 47 are rigidly supported from the first disc 44 as by bolts 48, spacers 49 and 50 preferably being used to properly accomplish the spacing between the discs. The disc 44 is provided with a number of equally spaced lugs 51 and the discs 46 and 47 each with an equal number of arcuate pockets 52, the assembly formed by the three discs forming a drum adapted to receive the bottles or cans in succession from the shelves of the storage chambers. 53 are retaining rods disposed around and adjacent the lower half of each of the two discs 46 and 47, the rods 60 being so bent and positioned as to be concentric with these discs and being adapted to retain articles in the pockets of the discs during their movement around the lower half of the drum.

The rods 53 terminate at 53-A where they are joined to a chute 54 leading through a suitable opening in the front wall of the casing 10. Extending upwardly and somewhat rearwardly from the junction of these rods and the chute is a division wall 55. The upper end of this wall abuts the underside of the top 11 of the casing, the wall extending from side wall to side wall of the casing. The division wall 55 is provided with rectangular apertures 56 each alined with a chute, these apertures being closed by doors 57, secured along their upper edges to the division wall 55 as

by hinges 58, and being adapted to open outward under thrust of a bottle or other article being discharged and to reseat and close the aperture by the action of gravity. Extending at a right angle from the division wall 55, and vertically downward therefrom are plates 59, each of these plates having a flanged edge portion 60 through which attachment is made to the division wall 55 as by rivets 61. For each unit there are a pair of these plates which preferably lie adjacent the two discs 46, 47 respectively. These plates project downward into the path of the pockets 52, and have each an arcuately curved edge 62 which edges act as guides to dislodge the articles 35 in succession as they are moved into guide engagement by turning movement of the drum, one of these articles 35—A being shown in Figs. 1 and 6 as it tangentially contacts the guide surfaces.

63 are a pair of rods which are secured to and depend from a horizontally disposed pivot rod 64, 20 also into the path of the articles 35, the lower end of these rods lying substantially flush with the lower ends of the guide surfaces 62. The pivot rod 64 is pivotally mounted in the two plates 59, one end 65 of this rod being bent at 25 right angles and extending vertically upward into the path of a pin 66 carried by a plunger arm 67. The plunger arm 67 passes through the plate 55 and is connected by a pin 68 with an operating plunger 69 which extends through the front of the casing 10 and carries on its outer end, a button 70 which is manually operable. The arm 69 is unlocked or otherwise controlled for movement by a coin actuated mechanism 71 of an usual and well known type such as that described in Patent No. 2,025,921, January 7, 1936.

The inner end of the plunger arm 67 rests on the periphery of the disc 44 and is adapted to slide along the periphery of the disc into engagement with the lugs 51 of the disc in succession, 40 and after such engagement, advance the disc a full lug space.

72 is a cam attached to the plunger arm 67 by a pin 73. 74 is a stop limiting backward movement of this cam, the cam being held there- 45 against by a spring 75. 76 is a detent arm having one end connected as by a bracket and pin 77 to the division wall 55 and having its opposite end downwardly turned to form a detent 78 adapted to ride on the disc 44 and successively 50 engage the lugs 51 to limit movement of this disc. The detent 78, as shown in Fig. 8, may be notched to fit over the disc 44 and prevent lateral displacement. 79 is a cam member secured to the arm 76, this cam member being engageable by 55 the cam 72 as the arm 67 slides forward along the disc 44 into engagement with the lug 51 to raise the detent 78 from engagement with the disc and lugs and permit advancement of the disc by the arm 67.

The chutes 54, as seen in plan in Fig. 2, have side walls 54-A, 54-B which converge toward the discharge end 54-C of the chute. The side walls are spaced apart adjacent the door 57 a sufficient distance to receive therebetween a package discharge through the door opening and lying transversely across the chute. Immediately adjacent this door opening is a lug 80 which is secured to and projects inward from the side wall 65 54-A, and is adapted to engage an end of the package and retard movement of such end, the opposite end of the package continuing its discharge movement and the package swinging into position for longitudinal movement through 70 75

chute and delivery in such position at the discharge end 54—C.

81 is a dog having one end riding on the disc 44 and adapted to engage the lugs 51 successively against retrogressive movement. The opposite end of the dog is hingedly secured by a pin 82, to a bracket 83, suitably secured to the division wall 55. 84 is a spring urging the dog 81 into disc and lug engagement.

10 85 are signal lights on the front of the casing, there being one such light for each unit, and these lights each indicating when they are burning that the unit is empty. Associated with each unit is a switch, shown in Fig. 7, which is held open by the packages and which closes when the unit is empty. In this switch 86 is a light circuit leading to a pair of contacts 87 which are carried by an insulated block 88. 89 is a circuit leading from these contacts to the signal light. 90 is an insulated contact bar carried by an arm 91 which is pivotally mounted on the division wall 55 as by a pivot pin 92. The opposite end 93 of the arm 91 contacts the ends of the packages being dispensed and holds the contact bar 90 away from the contacts 87. 94 is a spring urging the contact bar 90 against the contacts to close the circuit.

In use the top 11 is opened. The shelves 23, 24 and 25 of a holder are turned back about their hinges and a tier of the bottles or cans laid along the bottom 22 of the holder, one of these articles ordinarily rolling into a pocket of the drum. The shelf 23 is then turned about its hinge until it rests on the transverse rod 26 and is covered with an additional tier of the packages, one of these ordinarily also going into a pocket of the drum, and the two outer packages on the shelf, being those adjacent the drum, deflecting the flexible extension 31 into holding engagement with the outer package of the bottom tier of the holder. The other shelves are then successively turned down and filled, after which the drum is turned, the packages rolling off of the top shelf 25 across the flexible extension 33 and into the pockets of the drum until all the pockets therein are filled. Should the supply of packages on the top shelf be exhausted before this filling is completed, the flexible extension 33 will swing upward as the last package 50 therefrom goes into the drum pockets, and release the underlying article adjacent the drum and on the next lower shelf, so that these packages in turn will also go into the drum. When the drum has been entirely filled the shelves 55 are refilled for storage purposes and this particular unit of the device is ready for use. Each of the remaining holders is then similarly filled, and these units also made ready.

If it has not already been done the casing is 60 filled with liquid up to the level of the bottom of the door opening 56, the liquid used preferably being a mixture of water and salt which will permit chilling without freezing of the chilling liquid. The refrigerating outfit 15 may 65 then be started and the temperature of the liquid in the tank be reduced to the desired point.

When the packages are thoroughly chilled, vending may be begun. This is accomplished by dropping a nickel or other suitable coin in 70 the coin slot of the mechanism 11 to unlock or operatively couple the plunger 69 for use.

The plunger is pushed in, such movement through the cam 12 and cam member 18 raising the detent arm 16 and its detent 18 to allow 75 drum movement, and on continued movement

of the plunger shifting the drum. As this shifting movement progresses, the cam 12 passes the cam member 18 and allows the detent arm 16 to drop back on the disc 44 with detent 18 in position to limit and stop the disc movement. 5 During movement of the drum a package, as the package 35—A of Figs. 1 and 6, comes against the guides 62 and is deflected out of the pocket in which it is seated and against the door 57. Concurrently the pin 66 engages the upturned 10 end 65 of rod 64, causing the rod ends 63 secured to and depending below rod 64, to forcibly eject the article 35—A through the door opening 56, displacing the swinging door 57 in so doing. A package so ejected starts to roll down the 15 chute 54 but one end is almost immediately engaged by the lug 80, whereas the opposite end continues its downward movement and the package is longitudinally aligned with the chute and completes its movement toward the lower end 20 of the chute by sliding motion. After ejection of the bottle the door 57 swings back into place closing the interior of the casing against the outside air. Retraction of the plunger completes the operation, in such action the cam 12 25 tripping against the cam member 18 without raising the detent arm 16 or disengaging the detent 18.

Subsequent actions or repetitions may be performed until all the bottles have been discharged, 30 at which time the contact bar 90 is swung by the spring 94 against the contacts 87 and the circuit completed to the light 85 giving visual warning of the exhaustion of the supply and of the necessity of replenishing the stock. 35

We claim:

1. In a dispensing device, a casing, a drum mounted therein and rotatable about a horizontal axis, said drum having around its periphery a plurality of equally spaced pockets, means cooperating with said drum for confining packages to said pockets, a division wall within said casing forming a substantially tangential extension of said confining means, said division wall having an opening therethrough for discharge 40 of packages from said pockets, a closure door for said opening hinged along the upper edge of said opening, a discharge chute leading from said opening through a wall of said casing and terminating therewithout, guide means carried 45 by said division wall and extending into the path of movement of said pockets, said guide means curving arcuately upward and outward to the upper edge of said division wall opening, means for advancing said drum, and means cooperating with said drum advancing means for accelerating the ejection movement through said opening of packages deflected from said pockets by said guide means. 55

2. In a dispensing device, a casing, a drum mounted therein and rotatable about a horizontal axis, said drum having around its periphery a plurality of equally spaced pockets, means cooperating with said drum for confining packages to said pockets, a division wall within 60 said casing forming a substantially tangential extension of said confining means, said division wall having an opening therethrough for discharge 65 of packages from said pockets, a closure door for said opening hinged along the upper edges of said opening, a discharge chute leading from said opening through a wall of said casing and terminating therewithout, guide means carried 70 by said division wall and extending into the path of movement of said pockets, said guide 75

- means being curved arcuately upward and outward to the upper edge of said division wall opening, means for advancing said drum, means for limiting the advance movement to a single pocket space, and means cooperating with said drum advancing means for accelerating the ejection movement through said opening of packages deflected from said pockets by said guide means.
3. In a dispensing device, a casing, a drum mounted therein and rotatable about a horizontal axis, said drum having around its periphery a plurality of pockets, means cooperating with said drum for confining packages to said pockets, a division wall within said casing forming a substantially tangential extension of said confining means, said division wall having an opening therethrough for discharge of packages from said pockets, a closure door for said opening hinged along the upper edge of said opening, a discharge chute leading from said opening through a wall of said casing and terminating therewithout, guide means carried by said division wall and extending into the path of movement of said pockets, said guide means being curved arcuately upward and outward to the upper edge of said wall opening, and being adapted to eject articles therethrough, and means for advancing said drum.
4. In a dispensing device, a casing, a drum mounted therein and rotatable about a horizontal axis, said drum having around its periphery a plurality of pockets, means cooperating with said drum for confining packages to said pockets, a division wall within said casing forming substantially an extension of said confining means, said division wall having an opening therethrough for discharge of packages from said pockets, a closure door for said opening hinged along the upper edge of said opening, a discharge chute leading from said opening through a wall of said casing and terminating therewithout, guide means carried by said division wall and extending into the path of movement of said pockets, said guide means being adapted to divert packages from said pockets and discharge them through said wall opening, and means for advancing said drum.
5. In a dispensing device, a casing, a drum mounted therein and rotatable about a horizontal axis, said drum having around its periphery a plurality of equally spaced pockets, means cooperating with said drum for confining packages to said pockets, a division wall within said casing, said wall having an opening therethrough for discharge of packages from said pockets, and a closure door for said opening, said door being hinged along the upper edge of said opening to permit said discharge, means for diverting packages successively from said pockets through said wall opening, and means actuated by said drum advancing means for accelerating through said opening, the ejection movement of packages deflected from said pockets by said diverting means.
6. In a dispensing device, a casing, a drum mounted therein and rotatable about a horizontal axis, said drum having around its periphery a plurality of pockets, means cooperating with said drum for confining packages to said pockets, a division wall within said casing forming an extension of said confining means, said division wall having an opening therethrough for discharge of packages from said pockets, a closure door for said opening hinged along the upper edge of said opening, a discharge chute leading from said opening through a wall of said casing and terminating therewithout, means for advancing said drum step by step, a pair of spaced members secured to the inner face of said division wall and extending downwardly into the path of said pockets, said members each having an edge portion curving upwardly and outwardly from its lower end to engagement with said division wall at the upper edge of said wall opening, a horizontally disposed rod having opposite end portions journaled in said members, and a pair of integrally secured fingers depending from said rod substantially along the lower ends of the arcuately curved surface of said members, said rod having one end upwardly turned and extending into operative engagement with said drum advancing means.

LUE O. GARNER.
FRED MONTESI.
